UNITED STATES PATENT OFFICE.

IRVING A. NEWCOMER, OF MONROE, MICHIGAN, ASSIGNOR TO THE CONSOLIDATED PAPER COMPANY, OF MONROE, MICHIGAN, A CORPORATION OF MICHIGAN.

LAMINATED-PAPER MACHINE.

Application filed November 29, 1926. Serial No. 151,499.

My invention has for its object to produce an efficient wet machine for making laminated paper direct from the pulp and forming two or more laminations while in the wet state on a making roll. More particularly, the invention has for its object to produce such a machine for making waterproof laminated paper direct from pulp of different kinds and forming two or more laminations of different kinds of fibre paper while in the wet state on a making roll.

The invention provides means whereby the pulp is formed in layers on the felt belt and then delivered therefrom to the pressure roll or cylinder.

The invention may be contained in paper making machines that vary in the details of their construction and to illustrate a practical application of my invention I have selected a construction containing the invention and shall describe it hereinafter. The structure selected is shown in the accompanying drawings.

Fig. 1 illustrates a side view of a machine for integrating two layers of paper. Fig. 2 illustrates a top view of the machine shown in Fig. 1. Fig. 3 illustrates a side view for integrating three layers of paper.

In the example of construction selected, the invention is embodied in a paper machine of the well known type. It has the frame 1, the super-structure 2 and a plurality of pulp vats, such as, the pulp vats 3 and 4 in the form shown in Fig. 1 and 5, 6 and 7 in the form shown in Fig. 3. The frame 1 has the usual making roll 8 of hard maple that is subjected to pressure by the hand screws 9 so as to press against the pulp on the felt as it passes over the press roll 10 which enables the removal of the pulp from the felt.

The felt belt 15 passes over the pulp delivering cylinders 16 and 17 having wire mesh for gathering pulp from the vats 3 and 4. It is driven by rotation of the making roll 8 and the press roll 10. It passes over suitable guide and stretch rolls 18 and over the cylinders 16 and 17 where it gathers the pulp. It is pressed against the cylinders by the load on the rolls 19 and 20 at a point beyond the vertical center line of the cylinders. The load may be adjusted and the rolls 19 and 20 may be raised by raising the

arms 21 and 22. Cables 23 and 24 are connected to the ends of the arms and to a suitable drum or shaft 11. They pass over suitable guide blocks 12. When the drum is rotated the arms are raised and the felt is slackened which gives opportunity to clean out, change pulp, etc. The drum may be operated by a suitable hand wheel 25, sprocket belt 26, and gears 27.

Between the rolls 19 and 20 a portion of the water is removed from the pulp by drainage that is taken up by the felt to enable the pulp and felt take up an additional layer of pulp from the cylinder 20. Preferably the felt is inclined upward between the rolls 19 and 20 at a slight angle such as between 7 degrees and 20 degrees. This will depend on the character of the pulp taken from the vat 3. In the construction shown the felt is inclined to the horizontal about 10 degrees which will cause a suitable amount of water to drain from the first layer of pulp to enable it, with the felt and the pressure of the roll 20, to take off the second layer of pulp. The pulp is then carried to the making roller and pressed and gathered and removed in one or more double layers in the manner well known in the art.

In the form of construction shown in Fig. 3, the felt gathers pulp from the cylinders 28, 29 and 30 located in the pulp vats 5, 6 and 7. The felt 31 is inclined upwards at a slight angle between the succeeding cylinders so as to remove a required amount of water from the pulp previously gathered. Depending upon the character and thickness of the pulp, the felt may be given a slightly greater inclination between the rolls 29 and 30 than exists between the rolls 28 and 29, if desired. The structure has the additional pivoted arm 34 and cable 32 for supporting and manipulating the roll 33.

The machine is particularly designed for combining together a paper known as asphaltic paper that contains a relatively large percentage of asphaltum and a long fibre with a paper that is known in the trade as "buck fibre". The asphaltic pulp is placed in the first vat, namely, the vat 3, and is gathered from the pulp cylinder 16 on the felt belt 15 which is inclined upwards at a slight angle towards a point above the vat 4 that contains the "buck fibre" pulp and

gathers the "buck fibre" pulp from the cylinder 17. Owing to the inclination of the felt belt and the layer of asphaltic pulp between the two gathering cylinders 16 and 17, 5 water drains back until the amount in the pulp that is on the belt, as it gathers the "buck fibre", has been reduced to such an extent that the "buck fibre" pulp will be taken up and carried to the making roll 8. 10 This back wash or movement of the water, as it drains from the asphaltic pulp, lays the long fibre of the asphaltic pulp along the under surface so that it will intermingle with the exceedingly short fibre of the "buck fibre" pulp and when the two layers are 15 taken off from making roll 8 they will be bonded together by the long fibre as well as by the adhesive characteristics of the two pulps. When a board that is formed of 20 layers of "buck fibre" only is dried it warps and distorts owing to its shortness of fibre while on the other hand when a board is formed of a plurality of pairs of layers of "buck fibre" and asphaltic paper, it will not 25 deform when dried because of the interbond-

ing produced by the long fibres of the asphaltic pulp.

I claim:

1. In a paper making machine, a felt belt, guide rolls and making and pressure rolls, a 30 pair of pulp gathering rolls, one for gathering short fibre paper pulp and the other for gathering an asphaltum pulp containing long fibres, the felt inclined at an angle between 5 degrees and 20 degrees to the horizontal between gathering rolls and directed to the press and making roll.

2. In a paper making machine, a felt belt, guide rolls and making and pressure rolls, a 40 pair of pulp gathering rolls, one for gathering short fibre paper pulp and the other for gathering an asphaltum pulp containing long fibres, the felt inclined at an angle of ten degrees to the horizontal between gathering rolls and directed to the 45 press and making roll.

In testimony whereof I have hereunto signed my name to this specification.

IRVING A. NEWCOMER.
